UNITED STATES PATENT OFFICE.

WILLIAM KENNETH DALZELL, OF BARCALDINE, QUEENSLAND, AUSTRALIA.

MULTICYLINDER ROTARY INTERNAL-COMBUSTION ENGINE FOR AEROPLANES AND THE LIKE.

1,270,500.

Specification of Letters Patent. Patented June 25, 1918.

Application filed November 4, 1915. Serial No. 59,509.

To all whom it may concern:

Be it known that I, WILLIAM KENNETH DALZELL, a subject of the King of Great Britain, residing at Dalgi, Barcaldine, in the State of Queensland and Commonwealth of Australia, have invented Improvements in Multicylinder Rotary Internal-Combustion Engines for Aeroplanes and the like, of which the following is a specification.

This invention relates to improvements in multi-cylinder rotary internal combustion engines such as are ordinarily used for aeroplanes and the like. In the multi-cylinder rotary engines as used at present the cylinders are affixed to a drum or crank case resting on journals on the crank shaft, the latter being held stationary in the frame of the aeroplane, the cylinders revolving on their journals. In the usual four cycle principle of operation, each cylinder receives an impulse from the explosion every second revolution. Thus with a four cylinder engine two explosions occur every revolution.

In an engine constructed in accordance with my invention both the drum to which the cylinders are bolted, and the crank shaft are rotatable, the drum, supporting the cylinders, being journaled in bearings carried in the frame of the engine while the crank shaft is journaled in bearings carried in the end of the drum. The cylinders are connected to the crank shaft through a train of bevel wheels in such a way that for each turn in any direction of the former, the latter revolves a turn in the opposite direction. In this way although the cylinders revolve a given number of revolutions in respect to the stationary frame of the machine, they revolve twice that number with respect to the crank shaft. In this manner with a four cylinder engine four explosions occur every revolution, and thereby the power obtained from my engine is largely in excess of that obtained from any engine of the same size as at present in use.

Referring to the drawings hereto annexed in which the same reference numerals indicate the same parts wherever they occur:—

Figure 1 is a side elevation of a multi-cylinder rotary internal combustion engine made according to my invention.

Fig. 2 is a plan view of Fig. 1.

Fig. 2^a is a detail view showing on an enlarged scale the construction of certain parts 55 illustrated in Fig. 2.

Fig. 3 is a vertical section of the engine on the line of the crank shaft axis.

Fig. 4 is an enlarged view of one of the end bearings of the crank shaft showing the 60 gas ducts therein.

Fig. 5 is a sectional view of the gearing between the cylinders and the crank shaft and the bearing adjacent thereto.

Fig. 6 is a transverse section showing the 65 means of attaching the connecting rods to the crank shaft.

Fig. 7 is a longitudinal section of same.

1, 2, 3, and 4 are the cylinders which are connected to the drum 5 by means of their 70 lower ends passing through sleeves and projecting into and being bolted to said drum 5. The cylinders, 1, 2, 3, and 4, are, as illustrated, spaced at equal distances apart circumferentially, while each pair of cylinders, 75 viz: 1 and 3 and 2 and 4, are placed opposite their respective cranks 6 and 7 on the crank shaft 8, as shown more clearly in Fig. 3, where the cylinders 2 and 4 are directly opposite the crank 7, while the cylinders 1 80 and 3 (the latter not shown in that figure) are opposite the crank 6. Thus two connecting rods 38 are journaled on each crank as is usual with cylinders placed in opposition. The drum 5 revolves on ball bearings 85 9 which are supported on projections 10 formed on the side of the drum. The ball bearings 9 are carried in the frame member 19 on one side and 37 on the other side. To the said drum 5 on one side thereof is bolted 90 a bevel gear wheel 11 which gears with one or more wheels 12 turning on idler axles 44 in a chamber 13 affixed to the stationary frame member 37 formed to receive it. The idler axles of the wheels 12 are supported at 95 their inner ends by bearings 47 fitted into sleeve 32.

This wheel 12 again gears with a wheel 14 keyed to the crank shaft 8. Consequently for every revolution of the bevel gear wheel 100 11 in one direction, the wheel 14 moves one revolution in the reverse direction. The crank shaft 8, at the end to which the bevel wheels before mentioned are fitted, passes through a sleeve 32 which is held stationary 105 by being bolted to the member 37 of the

engine frame, the means of fixing are not seen in the drawing, the Fig. 5 being in section. This sleeve 32 holds at each end ball bearings 46 on which the crank shaft 8 revolves. The sleeve itself is journaled in ball bearings 15 which are held by the sleeve and a recess 16 formed in the side of the drum. The cams 29 operating the exhaust valves are fixed to the stationary sleeve and lift the valves in rotation. The bevel geared wheels 11, 12, and 14 hold the cylinders 1, 2, 3, and 4 and the crank shaft 8 in their respective positions, and also when in motion transmit the power from the said cylinders to crank shaft 8. One of the pinion wheels 12 has connected to it an extended shaft 28 which drives the magneto 17 which is secured to the stationary frame member 37 of the engine. In order to supply the cylinders 1, 2, 3, and 4 with petrol the bearing on one side is formed as shown in Fig. 4. The crank shaft 8 passes through the projection 10 of the drum 5 and runs on ball bearings 15 held by the said axle and a recess 16 formed in the drum 5. 18 is a carbureter which is fitted to one of the stationary members of the engine or the frame member 19. Through the said carbureter the air and petrol constituting the explosive mixture are drawn in and pass therefrom through pipe 20 to the bearing referred to which is formed with a hollow casing 21 leading to ducts 22 bolted inside on to one end of the drum 5. The said ducts 22 lead radially to transverse pipes 23 conveniently fitted to the inside of the drum 5 and so arranged that the branches 24 may be taken off as at 25 to feed the cylinders through the inlet valve 26 at the heads thereof. The pipes 23 also act as tie bolts and hold the ends of the drum together, as shown clearly in Figs. 2 and 2^A, the latter figure also showing the manner in which the pipes 23 are connected to the ducts 22. The exhaust valves 27 are operated by means of cams 29 and one or more radial rockers 30 fitted to and working in the end of the drum directly under the exhaust valves of cylinders 2 and 4 in the usual manner. The exhaust valves of cylinders 1 and 3 are operated by means of double rockers 31 (shown dotted in Fig. 2) which are fastened to the inside shell of the drum 5. The inlet valves 26 are placed immediately above the exhaust valves 27. The distributor wire 33 from the magneto is led along one of the stationary members to the terminal 34 which is made to contact with a fiber or similarly insulated distributor 35 connected by radial wires to the various sparking plugs 36. The whole engine is supported on each side by long and wide arms 19 and 37 with ball bearings 9 in each for the drum projections 10 to revolve on, the ends of the arms 65 being held in position by cross pipes 39.

Each pair of piston rods 38 connect on the center of their respective cranks immediately opposite each other by the end of one overlapping the other as indicated at 40. 41 is the pipe for supplying oil to the cylinders cranks and inner workings. This pipe is fastened into the end of the drum casing and connects with the drum axle 8 and passes through a stuffing box 42 from the oil cup and force pump 43. 44 is the handle for advancing or retarding the magneto spark and which handle passes through pipe 39. Through the said pipe also passes the insulated wire 33 from the magneto to the terminal 34. 45 is the handle operating the carbureter 18.

By my invention twice the relative movement of the cylinders and crank shaft is obtained for a given number of revolutions of either, and thereby twice the power from a given size of engine is obtained. It is well known that higher efficiency is obtained with air propellers operated at medium speeds than at high speeds. It is also desirable to obtain from an engine the greatest power per pound weight. With my engine both these results are obtained as it gives twice the power of the usual type of engine of the same size, and also drives the propeller at its most efficient speed.

What I claim as my invention, and desire to secure by Letters Patent, is:—

1. A rotary engine comprising a plurality of rotating cylinders, a drum integral with said cylinders, a hollow casing forming a bearing for said drum, transverse pipes on the inside of said drum, said drum having ducts communicating with said hollow casing and with said transverse pipes, inlet valves for said cylinders, and further pipes communicating with said transverse pipes and with said inlet valves.

2. A rotary engine comprising a plurality of rotating cylinders, a drum integral with said cylinders, a hollow casing forming a bearing for said drum, transverse pipes on the inside of said drum, said drum having ducts communicating with said hollow casing and with said transverse pipes, inlet valves for said cylinders, further pipes communicating with said transverse pipes and with said inlet valves, a transverse power shaft having one bearing in the drum, a support for said engine, said shaft having its other bearing in said support, a gear integral with said shaft, an opposing gear integral with said drum and an intermeshing gear mounted on said support, said intermeshing gear connected to a current generator.

3. A rotary engine comprising a plurality of rotating cylinders, a drum integral with said cylinders, a hollow casing forming a bearing for said drum, transverse pipes on the inside of said drum, said drum having ducts communicating with said hollow cas-

ing and with said transverse pipes, inlet valves for said cylinders, further pipes communicating with said transverse pipes and with said inlet valves, a transverse power shaft and a current generator having a differential planetary connection with said shaft and said drum.

In testimony whereof I have signed my name to this specification in the presence of two subscribing witnesses.

WILLIAM KENNETH DALZELL.
